GASOLINE DISPENSING VEHICLE

Joe S. Cline, Oklahoma City, Okla.

Application December 16, 1957, Serial No. 48,901

Term of patent 14 years

(Cl. D14—3)

Figure 1 is a perspective view showing my design for a gasoline dispensing vehicle;
 Figure 2 is a top plan view;
 Figure 3 is a side elevational view;
 Figure 4 is a front elevational view; and
 Figure 5 is a rear elevational view of the same.
 I claim:
 The ornamental design for a gasoline dispensing vehicle, as shown.
